UNITED STATES PATENT OFFICE.

FREDERIC E. BERTRAND, OF LYNN, MASSACHUSETTS, ASSIGNOR TO UNITED SHOE MACHINERY CORPORATION, OF PATERSON, NEW JERSEY, A CORPORATION OF NEW JERSEY.

CHANNELING MACHINE.

Application filed November 20, 1918. Serial No. 263,389.

To all whom it may concern:

Be it known that I, FREDERIC E. BERTRAND, a citizen of the United States, residing at Lynn, in the county of Essex and State of Massachusetts, have invented certain new and useful Improvements in Channeling Machines; and I do hereby declare the following to be a full, clear, and exact description of the invention, such as will enable others skilled in the art to which it appertains to make and use the same.

This invention relates to machines for operating on or fitting the soles of boots and shoes, and more particularly to channeling machines for fitting turn soles and insoles prior to their incorporation in the boot or shoe. Other special uses of the invention will appear from the following description.

One type of sole channeling machine at present in commercial use for both turn sole and insole work, known as the "Universal" channeling machine, is illustrated in the present inventor's prior patents No. 1,023,801, April 23, 1912, and No. 1,030,704, June 25, 1912. This type of channeling machine is so designed that the usual toothed feed wheel, which acts on the between substance, is eliminated and in its stead the smooth-faced pressure gages, which cooperate with the edge and channel knives, are utilized as feeding devices. In such machines the sole is fed across the work support by a movement of the pressure gages and knives in the line of feed and after the feeding movement is completed a presser foot descends to hold the sole from movement on the table while the cuts are made on the back, or idle, stroke of the feeding devices. In channeling the curved portion of the sole margin the sole is turned by the operator, relatively to the line of feed, during the forward stroke of the feeding devices since at other times the sole is held firmly on the work support and no angular movement thereof is possible. As is customary and necessary the pressure gages are held yieldingly on the sole, springs for this purpose being provided which bear on the slides which support the gages.

It has been found in operating machines of the type wherein a turning movement must be given to the sole while yieldingly engaged by the pressure gages, which determine the depth of the cut or otherwise hold the sole in proper relation to the cutting

devices, that the yielding gages permit an unskilled operative to buckle or distort the sole by unduly crowding it against the edge gage. The results of such a practice are serious as any unusual movement of the pressure gages disturbs their proper relation to the sole and on the cutting stroke will cause the knives to dig in and make an improper cut. This causes cripples and wasted work and material.

One object of the invention is to prevent an occurrence of the condition just described. To this end one feature of the invention provides mechanism which will prevent any buckling or distortion of the sole should the operative crowd it against the edge gage while turning it during the feed. The mechanism in question comprises a construction and arrangement through which the pressure gages are automatically locked against any vertical movement during the periods consumed in feeding the sole. This changes the yielding nature of the gages, essential to making the cuts but unnecessary while feeding, to a fixed or rigid nature and effectually prevents any distortion of the sole from its normal flat condition.

In making turn soles for sewed heel-seat work the shoulder cut is frequently omitted about the heel seat. To produce such a fitting of turn soles the shoulder knife is wholly removed from working position while channeling the heel-seat. In this type of turn sole the channel is cut farther in from the edge at the heel seat than around the forepart. Usually the base of the channel is $\frac{5}{16}$ " (allowing $\frac{1}{16}$ " for the thickness of the between substance) from the edge of the sole throughout the forepart and shank, and $\frac{5}{16}$ " from the edge of the sole at the heel seat. The change in the position of the channel is obtained by withdrawing the edge gage from the knives, as is usual in channeling machines. Operatives describe this condition as "drawing on" at the heel-seat. After the heel-seat has been channeled and the shank at the opposite side of the sole is reached it becomes necessary to return the shoulder knife to working position and advance the edge gage to a position which again will produce a channel $\frac{5}{16}$ " from the sole edge. These operations have ordinarily been performed by hand through separate mechanisms for actuating the shoulder knife

and the edge gage. Those skilled in the art will understand the absolute necessity, in returning these devices to their former positions, of bringing forward the edge gage before the shoulder knife is dropped on the sole. If the edge gage is still moving forward when the shoulder knife meets the sole the knife will, until the gage reaches its forward position, cut through the between substance and thus produce a crippled sole. It is difficult for an operative to coordinate the two movements so that the edge gage will, without fail, be completely withdrawn, and thus properly position the sole beneath the shoulder knife, prior to the descent of the knife. Accordingly it has heretofore been proposed to mechanically connect the trains of mechanism which operate the shoulder knife and edge gage so that their movements may properly be controlled. Such proposals have not been entirely successful because the connecting mechanism has not been properly designed to effect the two movements in the required timed relation.

A further object of the invention is to perfect a controlling mechanism for the withdrawing and return movements of the shoulder knife and edge gage which will necessarily provide for a completion of the forward movement of the edge gage prior to the return movement of the shoulder knife. Accordingly a feature of the invention provides a single controlling device connected to both the edge gage and the shoulder knife operating mechanisms, and comprising devices which will lock and hold the shoulder knife in its raised position during the period of time that the edge gage is withdrawn and until said gage has been again returned to its forward position, when the lock is released and the knife again permitted to descend to its working position. Combined with this mechanism is a further feature of the invention comprising mechanism which permits a hand control of the edge gage through a limited movement and which may be used to enable the operator to "draw on" at the toe and produce a wider feather at this portion of the sole while the shoulder knife remains in operative position. Such wider feather at the toe is desirable to take care of the greater thickness of the lasted-in upper formed by the additional box toe materials.

A still further object of the invention is to enable operators to swing the soles being operated upon with greater accuracy when making the turn at the toe. To this end the machine may be provided with a centralized edge gage, that is, an edge gage arranged opposite the channel knife which constitutes the pivot on which the sole is swung. In the welt work machine the chamfer knife shown in said Patent No. 1,023,801 is omitted to permit the shifting

in position of the edge gage. This brings the edge gage beneath the edge knife and means is provided to maintain a contact between the top of the gage and the bottom face of the edge knife when either the knife or the work support is adjusted for different thicknesses of soles. This provision insures a sufficient abutment for all sole edges.

Certain modifications in the form of the channel knife and presser foot are desirable when operating on pointed toe work to avoid breaking the channel flap when swinging at the toe, and roughing or marring the sole edge, particularly on turn work. Accordingly, further features of the invention comprise an improved channel knife and an improved presser foot which, respectively, overcome the tendency of the channel knife shank to break the channel flap, and the liability of the presser foot to mar the sole edge when operating on pointed toe work.

To the accomplishment of these objects and such others as may hereinafter appear, as will readily be understood by those skilled in the art, the invention comprises the features and combinations of parts hereinafter described and particularly pointed out in the appended claims.

The preferred form of the invention is illustrated in the accompanying drawings, in which:

Figure 1 is a front elevation of the head of a channeling machine of the type illustrated in the patents hereinbefore referred to, having the improvements of the present invention incorporated therein. A feed stroke has just been completed and the pressure gage lock has been released preparatory to the commencement of a cutting stroke;

Fig. 2 is a rear elevation of said channeling head;

Fig. 3 is an end elevation of said channeling head, a turn sole being shown in position in each of said views;

Fig. 4 is a plan of said channeling head with the driving pulley partly broken away to show parts beneath it;

Fig. 5 is a plan of the parts below the line 5—5 of Fig. 1, the head frame being sectioned;

Fig. 6 is an elevation, enlarged and partly in section, illustrating the mechanism for locking the pressure gages. The gage lock has just been operated and a feed stroke is about to commence. The channel knife block with attached parts has been broken away, and also the supporting bracket for the speed changing control lever;

Fig. 7 is an enlarged horizontal section through the pressure gage locking mechanism and the driving shaft, a sole being shown in dotted lines in position to start the fitting operation;

Fig. 8 is an enlarged detail, in front ele-

vation, of the mechanism for controlling the movements of the edge gage and shoulder knife;

Fig. 9 is a vertical section on the line 9—9 of Fig. 8;

Fig. 10 is a front elevation, partly in section, illustrating the hand control of the edge gage;

Fig. 11 is a detail, in plan, of the parts shown in section on Fig. 10;

Figs. 12 and 13 are details, in plan, of a modified form of presser foot for use with soles having pointed toes;

Fig. 14 is a detail, in front elevation, of the presser foot shown in Figs. 12 and 13;

Fig. 15 is a detail, in plan, showing a modified form of channel knife for pointed toe work;

Figs. 16 to 19 are views of said modified channel knife, in elevation, from all four sides;

Fig. 20 is a detail, in elevation, of a centralizing edge gage as applied to a turn work machine; and

Fig. 21 is a plan of the parts shown in Fig. 20.

While certain features of the present invention are applicable to both turn and insole work, for the purpose of illustration the invention has been shown in a turn channeling machine of the type illustrated in the inventor's prior patents hereinbefore referred to as improved by the addition of the edge knife pressure gage shown in his prior Patent No. 1,030,710, June 25, 1912, and the substitution of the eccentric drive shown in his prior Patent No. 1,098,010, May 26, 1914, for the cam drive of the earlier patents. The type of machine illustrated is one well known to shoe manufacturers having been the standard power channeling machine for turn work for many years, therefore the main features of its construction, in connection with which the features of the present invention are employed, need be referred to but briefly. It will be apparent to those skilled in the art from the following description that certain features of the invention are useful in operating upon insoles for welt shoes and can as readily be incorporated in a welt work channeling machine as in a turn work channeling machine.

In the machine illustrated in the drawings, the operating head is adjustably supported upon a column 2 (Figs. 1 and 2) by means of an intermediate member 4 to which the head is bolted. The frame 6 of the operating head is of general U form and has mounted therein the operating tools and feed mechanism, said parts being located above a work supporting table 8 vertically slidable within a bracket extending from the base of the head. The table 8 is normally held in raised position by means of a toggle mechanism 10 through which it is lowered to remove work completed and insert new work beneath the operating tools. This table operating mechanism is similar to the same mechanism illustrated in the Meyer Patent No. 984,772, February 21, 1911, and is also embodied in the prior Bertrand patented machines. The channel knife 12 and the shoulder knife 14 (Fig. 2) are mounted upon knife blocks which are carried by the lower ends of independent slides 16 and 18 respectively (Fig. 6) vertically movable within a swinging carrier 20 which oscillates in the line of feed. The slides 16 and 18 are yieldingly urged toward the work table 8 by springs 22 and 24 respectively. The carrier 20 is pivotally supported upon a pair of horizontal bearings 28 (Fig. 1) near the upper end of the carrier. The channel knife pressure gage 30 (Figs. 2 and 3) is supported on the channel knife block and determines the depth of the channel cut from the upper or flesh side of the sole. The edge knife pressure gage 32 (Figs. 1 and 6) is mounted independently of the edge knife being carried at the lower end of a third slide 34 mounted in the oscillating carrier 20 and yieldingly urged toward the sole by a spring 36. In the rear, in the line of feed, of said knives and gages is a presser foot 38 (Figs. 1 and 6) yieldingly carried on a slide 40 by means of a spring 42. This foot is moved vertically toward and from the sole by means of an eccentric 44 (Figs. 6 and 7) on one end of the drive shaft 46. The other end of the drive shaft 46 is provided with a belt pulley 48 (Figs. 1 and 2). The carrier 20 is oscillated by connections thereto from a second eccentric 50 (Fig. 6). All of these parts may be and preferably are the same as described in said prior patents hereinbefore referred to, and they are operated in timed relation to feed the work in the following manner. With the oscillating carrier in its position shown in Fig. 6, that is at the end of its right-hand stroke viewing said figure, the presser foot 38 is held in raised position by its eccentric 44. The carrier 20 is then moved by its eccentric 50 to the end of its left-hand stroke, as illustrated in Fig. 3. The pressure gages 30 and 32, being continually in feeding engagement with the sole in moving from the position of Fig. 6 to that of Fig. 3, drag the sole forward across the work table 8. The angular position of the eccentrics 44 and 50 relatively to each other is such that upon the completion of the left-hand stroke of the oscillating carrier 20 the presser foot 38 has been lowered into engagement with the sole and by means of its roughened lower face holds the sole against movement while the carrier makes its right-hand stroke. On this stroke of the carrier the pressure gages yield as they slide backward over the sole while at the same time

the knives cut through the sole forming the channel and shoulder. This cycle is repeated at a rapid rate, the length of the feed stroke being comparatively short.

6 The edge gage 52 (Figs. 1, 2 and 5) is mounted upon an edge gage slide 54 provided with an upwardly projecting pin 55 which enters a bore in the lower end of the oscillating carrier 20. The edge gage is 10 thus moved in the line of feed with the knives toward and from the presser foot 38. The slide 54 is mounted upon a transverse slide 56 which is operated by mechanism similar to that described in the Meyer 15 Patent No. 984,773, February 21, 1911, and also embodied in the prior Bertrand patented machines, to move it across the line of feed and vary the margin of the sole determined by the line of cut made by the 20 channel knife. Certain improvements have been made in the edge gage operating mechanism which will be made clear hereinafter.

Of the new features of the machine that which will first be described is the mechanism 25 for automatically locking the pressure gages against any vertical movement during the periods consumed by the oscillating carrier 20 when feeding the sole. This locking of the gages is especially desirable 30 when operating upon fleshy sole stock. The rubbing action of the gages on the surface of such stock is quite liable to rough up the flesh and form a bunch which when passing under the channel gage will 35 lift it against its spring pressure and, because the channel knife rises with it, cause a thin channel to be cut. Sometimes also on stock of fleshy character the flesh will become so loose as to form a movable layer 40 between the pressure gages and the firm portion of the stock which will at times wholly nullify the feeding action of the gages. For these reasons, and those already explained, it is highly desirable that 45 the pressure gages be held rigidly in firm engagement with the sole stock during the feeding strokes of the oscillating carrier 20. It has been found convenient at the time desired to lock the gage supporting slides 50 against vertical movement within the carrier 20 and, since the nullification of the force of the pressure on the springs which impart vertical movement to the slides is an intermittent operation, the locking operation 55 must be accomplished in timed relation to the vertical movements of the presser foot 38. It has been found convenient to use the vertical movement of the presser foot as an actuator for the slide locking device.

The pressure gage locking mechanism is best illustrated in Figs. 2, 3, 4, 6 and 7, and referring first to Figs. 6 and 7, it will be seen that the edge knife pressure gage 60 slide 34 and the left-hand wall of the oscil-

lating carrier are bored to permit the insertion of a sleeve 58 held from rotary movement by means of a squared collar 60 which fits transversely a longitudinal recess formed in the slide 34. This recess is elongated somewhat longitudinally, as shown in Fig. 6, to permit such vertical play of the slide as may be required. The sleeve 58 is provided with an internal screw thread of steep pitch and threaded therein is a screw 62, one end of which bears upon a hardened wear piece 64 fitted into the face of the channel knife and channel pressure gage slide 16. To the outer end of the screw 62 there is rigidly secured a 70 crank arm 66 (Figs. 2 and 7). This crank arm is forked and has pivoted therein a forked knuckle 68 to which is pivoted the lower end of a vertical lock actuating rod 70, which, at about its center, has secured thereto a collar 72. Above the collar 72 is a coiled spring 74 surrounding the rod, borne upon by a slidable sleeve 76 having a pin 78 extending at right angles thereto. The pin 78 is journaled in a bearing 80 (Fig. 2) formed in the left-hand end 81 of an operating lever which, as best shown in Fig. 4, is provided with a pair of hubs 82 surrounding the bearings 28 of the oscillating carrier 20. These hubs are joined by a tie-plate 84 and the lever has a right-hand extension 86 to which is pivotally connected the upper end of a vertical link 88, the lower end of which is pivotally connected to the slide 40 which operates the presser foot 38. An adjustable collar 90 is threaded on the upper end of the lock actuating rod 70.

It will be observed that when the presser foot 38 is lifted, the lever 81-86 is rocked about the fulcrum of the oscillating carrier in a direction to bear downwardly upon the collar 72 which, being fast to the rod 70, moves this rod downward and rotates the crank 66 in a clockwise direction. The screw 62 being provided with a right-hand thread is thus moved forwardly within the sleeve 58 exerting pressure upon the wear piece 64 and through this pressure binding the slides 16 and 18 against each other and against the right-hand wall of the oscillating carrier 20. The fit of the slides within the carrier is close and therefore they can move laterally but slightly under the pressure of the screw 62. Almost immediately, therefore, after the screw has started its rotation it can advance no further and its pressure is then transmitted in an opposite direction through the sliding sleeve 58 to the edge knife pressure gage slide 34 which is pressed by the squared collar 60 against the left-hand wall of its slide-way on the oscillating carrier. In this manner a slight rotation in a clockwise direction of the crank 66 will bind all three of the 130

slides within the oscillating carrier against any movement in a vertical direction and this locking of the slides will endure until the eccentric 44 which operates the presser foot slide 40 rotates to a position which will cause the link 88 to draw the end 86 of the lever 81—86 downward. The spring 74 is interposed between the lever 81—86 and the collar 72 to take up and cushion the excessive throw imparted to the operating lever by the upward movement of the slide 40. Fig. 6 shows the slides locked, as just described, and the pressure gages about to start their feeding stroke. Fig. 3 shows the parts in the reverse position. In Fig. 3 the presser foot 38 is in contact with the work and holds it from movement, the oscillating carrier 20 is about to move to the right in order to make the channel and edge cuts and the lever 81—86 has been tilted about its pivot 28 by the downward movement of the presser foot slide 40 until the sliding sleeve 76 has engaged the fixed collar 90 and turned the crank 66 in a counter-clockwise direction sufficiently to remove all the pressures which had been exerted by the sleeve 58 and screw 62 upon the previous rotation of the arm 66 in a clockwise direction. It will be observed that the eccentricities 44 and 50 are so set angularly relatively to each other that the spring pressure upon the feeding pressure gages is wholly nullified during each feed stroke, that is, during the time when the sole must be turned about the channel knife as a center in guiding the various curves of the sole past the edge gage 52.

The illustrated machine is provided with the usual means for lowering the work support and lifting the knives when it becomes necessary to remove and insert work. This mechanism is best illustrated in Figs. 2 and 4 and is actuated by a foot treadle attached to a treadle rod 92 which is depressed in order to lower the work support and lift the knives.

The knives are lifted by the movement to the right of an arm 94 (Fig. 2) carried by one of the links of the toggle 10 which, through the links 96 and 98 and bell-crank 100 moves a horizontal arm 102 which is loosely pivoted upon a transverse shaft 104, downwardly about said shaft as a fulcrum. The arm 102 is provided with a pair of vertical set screws (Fig. 4) which bear upon tail pieces of levers 106 and 108 also loosely pivoted upon the shaft 104, the forward ends of which project beneath pins extending laterally from the channel knife slide 16 and shoulder knife slide 18 respectively. This mechanism is all as shown in said prior Patent No. 1,023,801, it being observed that when the treadle connected to the treadle rod 92 is depressed the levers 106 and 108 will be moved in a direction to lift the

knife slides against the force of their springs 22 and 24. Obviously, if the treadle is depressed at a time in the cycle of operations when the knife slide lock is in operation, difficulty will be experienced and possible breakage of the machine. Means is provided, therefore, for insuring a release of the locking mechanism at the time it is desired to exert pressure upon the slides to lift them. To this end the lever 102 is provided with an extension carrying a third set screw 110 (Fig. 2) which bears upon the tail piece of a third lever 112 loosely pivoted on the shaft 104. This lever has a forked end, through which the lock actuating rod 70 passes, located below the collar 72 on said rod. Now, when the work support lowering treadle is depressed the lever 112 is moved upward by the downward movement of the arm 102 concurrently with the levers 106—108 which movement if the lock is in operation, causes the arm 66 to be rotated in a counter-clockwise direction, the rod 70 being moved loosely upward through the sleeve 76. Thus, during the time when the knives and work support are retracted from each other, the locking device is maintained in its released position. Preferably the set screw 110 is so adjusted relative to the other set screws in the arm 102 as to move the lever 112 just prior to the movement of the levers 106—108, thus insuring that the locking device is released prior to any lifting pressure being exerted upon the knife slides. In its normal position, the forked end of the lever 112 is located a slight distance below the sleeve 72. This provides space for the required downward movement of the sleeve 72 when the lock is operated from the presser foot slide 40, without imparting movement to the lever 112.

As has heretofore been explained, in making turn soles for sewed heel-seat work, the shoulder is omitted around the heel seat, and the margin outside the channel cut is increased. To attain this result the shoulder knife is lifted from its operating position and the edge gage is retracted so that, the sole being kept in contact with it, the channel knife will cut further from the edge. Those skilled in the art will recognize the necessity of lifting the shoulder knife before the edge gage is retracted when channeling on to the heel-seat from the shank, and of advancing the edge gage before the shoulder knife is lowered into cutting position when channeling on to the shank from the heel-seat at the other side of the sole. If this timing of the two parts is not preserved the sole cannot be pushed back against the gage quickly enough to immediately obtain a wider margin when channeling on to the heel-seat. When channeling on to the shank again, if the knife should be dropped first, before the sole is again positioned for a

narrow margin, the between substance would be cut through.

The mechanism through which the proper timing of parts is secured is best illustrated in Figs. 1, 2, 4, 5, 8 and 9. In this mechanism the shoulder knife is, as usual, lifted by lowering a rod 114 (Fig. 1) which is connected to the end of a rearwardly projecting arm 116 secured to the transverse shaft 104. 10 A stop 118 limits the downward movement of the arm and a spring 120 acts to return the arm to its normal position when pressure on the rod 114 is relieved. A forwardly projecting arm 122 (Figs. 2 and 4) is secured to the other end of the shaft 104 and this arm bears beneath a pin 124 projecting laterally from the shoulder knife slide lifting lever 108. Thus, when the rod 114 is lowered, the shoulder knife only is lifted 15 from operating position leaving the channel knife unaffected since no movement is imparted by the mechanism just described to the channel knife slide lifting lever 106. This mechanism is all as illustrated in said prior Patent No. 1,023,801. In order that the locking device may be released so as to permit the shoulder knife to be lifted when desired, the lever 122 is provided with a laterally extending lug 126 20 (Fig. 4) located beneath a set screw 128 (Figs. 2 and 3) which is threaded through a lateral lug formed on the lock releasing lever 112. Thus the upward movement of the lever 122 to lift the shoulder knife slide 25 will at the same time lift the lever 112 and release the locking device so as to free said slide if the mechanism for lifting the slide should be operated at a time in the cycle of operations when the locking device is effective. 30

Heretofore, in applicant's patented machines a shoulder knife lifting treadle was connected directly to the rod 114 and the edge gage was operated only by the handle 130, the two mechanisms being entirely divorced from each other. In the present machine, however, as shown best in Figs. 1, 5 and 10, certain mechanical connections are interposed between the knife lifting rod 114 35 and the edge gage adjusting mechanism which provide for an operation of these two parts by a single means. These mechanical connections are so designed as to insure a concurrent lifting of the knife and withdrawal of the edge gage; and a concurrent lowering of the knife and advance of the edge gage, but each gage movement being so timed as to its partner of the couple as to insure a proper positioning of the work 40 for the operation of the knife without crippling the sole.

The edge gage adjusting mechanism is mounted in a bracket 132 (Figs. 1 and 5) extending forwardly from the work support 45 and comprises a rotary head 134 (Fig. 10)

secured to a vertical shaft 136 which extends downwardly through a sleeve 138 held fast, within a vertical bearing in the bracket 132, by means of a draw bolt 140. The bracket is provided with a segmental recess 142 (see 70 dotted lines Fig. 5) into which there depends a stop member 144 secured to the head 134. A wrist pin 135 on the head 134 is engaged by the forked end of a centrally pivoted lever 146 (Fig. 5) the other end of which is 75 provided with a toothed segment engaging a rack on the edge gage slide 56. With this construction when the head 134 is rotated in a clockwise direction, the lever 146 is rotated in a direction to advance the gage and position it for a narrow margin on the sole. When the head 134 is rotated in a counter-clockwise direction the gage is withdrawn across the line of feed for a wide margin on the sole. Ordinarily, the ends of the segmental recess 142 form stops which determine the amount of movement given the gage. This construction of the edge gage 80 adjusting mechanism is like that shown in the Meyer Patent No. 984,772, February 21, 1911, and also embodied in the prior Bertrand patented machines. 85

In the accompanying drawings, Figs. 1 and 4 show the edge gage in its advanced position and the shoulder knife in its operating position, and Figs. 5 and 8 show the edge gage in its retracted position at which time the shoulder knife is lifted. 90

The bracket 148, which supports the mechanism connecting the edge gage adjusting mechanism and the shoulder knife lifting mechanism, is shaped so as to fit the edge of the circular flange on the base of the U-frame 6, its form being well illustrated in Figs. 1 and 5. The bracket 148 is secured to the flange by a vertical bolt 150 and is adjusted about this bolt as a pivot by a set screw 153 which bears on the edge of the flange. The rotary head 134 of the edge gage adjusting mechanism is provided with a lateral ear 154 (Figs. 1 and 5) to which is pivotally connected a link 156 in turn pivotally connected to the left-hand end of an edge gage operating rod 158 (Figs. 1 and 8). The other end of this rod extends loosely through an opening in a block 160 which is provided with a lateral extending pin 162 received in a hub on the upper end of a vertically extending lever 164 pivoted loosely upon a horizontal rock-shaft 166 journaled by its ends in the bracket 148 (see Fig. 9). Integral with the lever 164 and extending downwardly below the shaft 166 is a lock-block 168. Pinned to the rock-shaft 166 is an arm 170, the free end of which is connected by a vertical link 172 to the free end of a second arm 174 secured at its other end to a short shaft 176 which is journaled in a depending portion 178 of the bracket 148. From the lever 174 120

a treadle rod 180 depends and is connected to an operating treadle (not shown) at the base of the column. The weight of the treadle parts is sustained by a coiled spring 182 connected at its lower end to the lever 174 and at its upper end to a pin projecting from the bracket 148. This spring normally holds the arm 174 in substantially horizontal position, as shown in Fig. 1, 5 against a stop screw 183 threaded into a lug 173 projecting from the portion 178 of the bracket 148. The arm 170 has a transverse lug 184 (Figs. 5 and 4) projecting from its rear side which carries an adjustable lock-block actuating screw 186 adapted to engage the rear side of the lock-block 168. The screw 186 is so adjusted that its end, when the parts are in the position shown in Figs. 1 and 4, is a short distance from the 10 lock-block, thus providing for short idle stroke before the block is engaged. The rock-shaft 166 has also secured thereto a depending arm 187 (see Fig. 9) the lower end of which is formed as a cam 188 (Figs. 2 and 8) which is adapted to ride over and depress a roll 190 rotatably mounted upon a pin projecting from the rear face of a slide 192 (Figs. 1, 8 and 9) constrained to move vertically in upper and lower guideways 15 193 and 194 formed on a vertical member 195 on the bracket 148. The slide 192 is provided with a vertical slot 196 through which the rock-shaft 166 passes, permitting movement of the slide past the shaft. The 20 lower end of the knife lifting rod 114 is hooked into the upper end of the slide 192 (see Figs. 1 and 9) so as to be actuated thereby. The slide 192 is located between the arm 187 and the lock-block 168 and on its side toward the lock-block it is provided with a vertical shoulder 198 (Figs. 1 and 8) 25 against which the lock-block bears when the parts are in the position shown in Figs. 1 and 4. The shoulder 198 is provided with a horizontal shelf 200 at its upper end and beside the shoulder, opposite the lock-block, is a stop screw 202 threaded into a lug depending from the bracket 148.

The spring 120 normally maintains the slide 192 and the arms 170 and 174 in their raised positions and consequently the shaft 166 rocked to a position with the cam 188 at one side of the roll 190 as shown in Figs. 1 and 4. A coiled spring 204 (Figs. 1 and 8) is connected by one end to a sleeve 208 secured to the rod 158 and by its other end to a sleeve 208 secured to the projecting end of the draw bolt 140, and thus tends continually to move the rod 158 to the left, in Fig. 1, and maintain the stop 144 (Fig. 10) against the left-hand shoulder of the segmental recess 142 in the rotary head 134 of the edge gage operating mechanism. Lock nuts 210 threaded on the free end of the rod 158 bear upon the pivotal block 160 and

act to move the lever 164 to the left with the rod 158. This position of the lever 164 normally maintains the lock-block 168 at the right, in Fig. 1, of the shoulder 198 on the slide 192.

In operating the mechanism just described when channeling on to the heel-seat from the shank, on depressing the treadle rod 180 the result is to first lower the slide 192 and lift the shoulder knife from its operating position. This lowering of the slide is effected by the rotation of the rock-shaft 166 and consequent movement of the cam 188 over the roll 190 which forces the slide downward. During this downward movement of the slide, there is no movement of the lever 164 and consequently no actuation of the edge gage adjusting mechanism. By the time the downward movement of the slide has caused the shelf 200 to come into the plane of the lower end of the lock-block 168 the screw 186 has been advanced far enough, through the movement of the lever 170 to engage the lock-block and force it to the left, in Fig. 1, into a position over the shelf 200 as shown in Fig. 8. A movement of the lock-block to the left moves the lever 164 to the right and consequently, by pressure against the lock nuts 210, moves the rod 158 to the right extending the spring 204 and rotating the head 134 in a counter-clockwise direction. This movement continues until the lock-block engages the stop screw 202. The shoulder knife is now out of operating position and the edge gage is withdrawn, to the position required for the wide margin around the heel-seat, the parts being in the position shown in Figs. 5 and 8. When the treadle is released the spring 204 immediately begins to contract which moves the lever 164 to the left, in Fig. 8, and carries the lock-block 168 to the right to remove it from the shelf 200. This turns the rotary head 134 in a clockwise direction and advances the edge gage across the line of feed to produce the narrow margin required around the forepart. No vertical movement of the slide 192 can take place, however, and consequently no lowering of the shoulder knife until the lock-block has been removed from its position upon the shelf 200. When the lock-block has been moved off the shelf the spring 120 immediately acts to pull the slide upward and permit the spring 24 to drop the knife into operating position, but the timing is such that this can not occur until after the edge gage has reached its final forward position. It will be observed that while the lock-block is moving to the right to free itself from the shelf 200, the cam 188 is also being moved to the right and withdrawn from above the roll 190 so that when actuation of the slide 192 commences its completion is quickly consummated, there being no parts in position 130

to prevent it from returning immediately to its raised position thus instantly permitting the shoulder knife slide spring 24 to act.

While ordinarily, in channeling turn soles, a single margin is used throughout the shank of the forepart and the margin is changed only for the heel-seat, in the better class of shoemaking manufacturers deem it desirable to increase the margin slightly around the toe to make room for the increased thickness of the upper materials at this point caused by the insertion of the stiffening materials which form the box toe. In order to permit the margin to be changed around the toe without removing the shoulder knife from its operating position, certain improvements are made in the edge gage adjusting mechanism which are shown best in Figs. 10 and 11. The vertical shaft 136 to which the rotary head 134 is secured has fastened to its lower end, by a draw bolt 212 (Fig. 11), a flange 214. The operating lever 130 is centrally pivoted on this flange and its end 216 opposite the handle is positioned so as to bear upon the lower end of a spring pressed pin 218 seated in a bore in the under side of the flange 214, and adapted to be projected by a movement of the lever through an opening in the upper surface of the flange and into a segmental recess 220 in the flanged lower end of the fixed sleeve 138. By depressing the handle 130 the pin 218 is projected into the recess 220 and the shaft 136 can then be rotated within the limits determined by the shoulders which form the ends of the recess. A rotation of the shaft 136 in this manner permits a withdrawal of the edge gage across the line of feed a sufficient amount to give the desired increased margin at the toe. The movement thus imparted to the head 134 actuates the rod 158 but due to the type of connection used between this rod and the upper end of the lever 164, the rod merely slides idly through the block 160 and imparts no movement to the lever.

When operating upon pointed or razor toe work, it is desirable to modify the shape of the presser foot 38 and of the channel knife 12. The modified presser foot is shown in Figs. 12 to 14 and the modified channel knife in Figs. 15 to 19. The sides of pointed toed soles slope so sharply toward each other at the toe that when the turn at the toe is made, as shown in Figs. 12 and 13, a presser foot of the form illustrated in Fig. 7, would entirely lose its bearing on the sole except for the small right angular leg 222. It so happens that the condition most frequently met with in making the turn is that illustrated in Fig. 13 when the sole is so positioned that the forward edge of the presser foot bears substantially upon the edge of the sole. It being remembered that the machine is run at

high speed, the result is that the rapidly reciprocating presser foot engages the edge of the sole a number of times before the operative can get it completely turned. Consequently, the margin is "chewed up" by the teeth on the presser foot and in particular the small leg 222 is apt to dig a hole in the margin. It is, therefore, desirable that the sole engaging portion of the presser foot be so shaped as to enable it to obtain a firm bearing upon the sole no matter what the shape of the sole may be or its position relative to the foot. To obtain this advantage, the foot 38 is provided with a supplemental foot or leg 224 extending at right angles to the main portion of the foot and of such length as to overlap the sole a considerable distance and provide a firm bearing in all positions which the sole assumes when turning at the toe. Its action is illustrated by Figs. 12 and 13 which show the two positions of the sole when turning at the toe which give the most trouble with the old type of foot employed for round toed soles. Since the foot or leg 224 extends so far forward as to lie beneath the oblique channel knife 12 the upper side of its inner surface must be beveled so that it can be located close to the point of operation of the knife. In the position shown in Fig. 13, the required length of the foot 224 causes it to overlap the channel flap which has just been formed by the channel knife. In order not to injure the channel flap the underside of the free end of the foot 224 is obliquely beveled as to 225 (Fig. 14). This construction enables the foot to clear the channel flap when the sole is in the position shown in Fig. 13.

Referring now to Figs. 15 to 19, each show the modified form of the channel knife. In operating upon pointed toe insoles the cut channel flap is at one time, during the turning of the sole at the toe, brought into parallelism with the shank of the channel knife. This condition is illustrated by Fig. 15. If a channel knife having a straight shank, such as is shown in Fig. 13, is used for pointed toe work, when during the turn the point just described is reached, the flap is forced upwardly and outwardly by pressure of the back of the knife shank and the force of the pressure is sufficient either to tear the flap or, if the stock be stiff and hard, to break the knife. Those skilled in the art will, therefore, recognize that it is highly desirable to employ a channel knife so shaped and constructed that room is provided for the channel flap to lie in the channel in all positions of the sole relative to the knife. To gain this end, the present inventor has so constructed the channel knife that its shank, which has heretofore extended in the general direction of the cutting edge 226 of the blade, is provided

with a crook 228 therein bowed toward the side of the cutting edge, thus forming a recess 230 in the back of its shank adjacent the heel 232 of the cutting blade. The portion 234 of the shank beyond the bow 228 is straight so that the knife may be clamped in the customary knife block. The recess 230, at 235 (see Fig. 19) where it joins the straight portion 234 of the shank, 10 is beveled so as to provide a smooth opening for the edge of the flap to pass through. In using this knife there is no danger of the channel flap being broken even on soles known as "razor" toes. The knife is particularly adapted for turn work where the weight of the sole produces a stiff channel flap.

It has been found that if the edge gage 52 is positioned, as is usual, in advance of the 20 cutting point of the knives, as shown in Figs. 12 and 13, some difficulty is experienced in turning the sole at the toe because the pivot about which the sole is turned is the end of the channel knife and the bearing to which the edge of the sole must be held is not directly opposite the pivot point. It is, therefore, proposed to change the location of the edge gage to a position centrally opposite the channel knife which will 25 be the preferred location of the gage for fine work. This modification is shown in Figs. 20 and 21. The centralized edge gage 236 is supported in a vertical dovetail way in a head 238 on the edge gage support 240 30 which is adjustably bolted, as usual, to the longitudinal slide 54. This position brings the edge gage beneath the shoulder knife. Its upper end is therefore beveled as shown in Fig. 20, to fit snugly against the under 40 side of the knife. In turn work the table is adjusted vertically relative to the knives for different weights of soles and since the edge gage support 240 is mounted upon the work support bracket 132 it will move vertically with the work support during such 45 adjustments. The work support adjusting mechanism, indicated generally by 242 (Figs. 1 and 3) is similar in principle to that disclosed in the Prenzel reissue Patent No. 50 13,375, February 27, 1912. To avoid a continual readjustment of the edge gage 236 so as to always maintain a sufficient bearing 55 face above the plane of the work support, whatever the height of the work support 60 may be relative to the knives, the edge gage 236 is made to slide vertically within the dovetail way in the head, 238. The gage is constantly urged upward by means of a coiled spring 244 seated in a recess back of the gage having its lower end secured to a pin projecting from the rear side of the gage shank and its upper end secured to the gage 65 block. With this construction, whatever vertical position the work support may assume, the gage is always held in contact with

the underside of the shoulder knife and consequently always affords a bearing for the entire sole edge.

When applying this centralized edge gage to the machine of the type shown in the accompanying drawings, since the shoulder knife travels in the line of feed in the arc of a circle and the edge gage travels in a right line path, it is necessary to back off the top of the gage at its forward edge so as 70 to permit the shoulder knife to swing across it without injury to the cutting edge of the knife blade. This, therefore, will be a feature of the centralized gage construction when applied to a channeling machine of the 75 type illustrated, whether it be for turn work or welt work.

Nothing herein contained is to be interpreted as limiting the invention in the scope of its application to use in connection with the particular machine, of the particular mode of operation, or both, selected for purposes of illustration and explanation. While the particulars of construction herein set forth are well suited to one mechanical form 90 of the invention, it is not limited to these details of construction nor to the conjoint use of all its features, nor is it to be understood that these particulars are essential since they may be variously modified within the skill 95 of the artisan without departing from the true scope of the actual invention, characterizing features of which are set forth in the following claims by the intentional use of generic terms and expressions inclusive of 100 various modifications.

What is claimed as new, is:—

1. A sole fitting machine having, in combination, a sole feeding means including a pressure gage normally urged yieldingly toward the sole, and having an intermittent feeding period during the operation of the machine, and means for locking the gage against any vertical movement during said feeding periods.

2. A sole fitting machine having, in combination, a spring-pressed slide, a pressure gage carried thereby, an oscillating carrier for said slide, means to oscillate said carrier, and means for locking said slide against any movement within the carrier at each successive movement of the carrier in one direction.

3. A sole fitting machine having, in combination, a sole feeding member held in engagement with the sole by spring pressure, means for reciprocating said member in the line of feed, and means for nullifying the force of said spring pressure on each alternate stroke of said member without changing the spring-pressed position of said member.

4. A sole fitting machine having, in combination, a pressure gage, a spring for holding said gage continually in engagement

105

130

- with the sole, and means acting intermittently to nullify the action of said spring and periodically lock the gage against any vertical movement.
5. A sole fitting machine having, in combination, a plurality of pressure gages each independently spring-pressed toward the sole, and a single means acting intermittently to nullify the force of the pressure from all of said springs and periodically lock the gages against any vertical movement.
10. 6. In a channeling machine of the type in which a knife and its pressure gage are reciprocated in the line of feed, said gage being spring-pressed and acting to feed the sole on one stroke, the knife performing its function on the other stroke, and a presser foot movable to intermittently engage the sole and hold it from movement during the cutting operation; the combination with said gage of means for changing the yielding nature of the gage to a fixed or rigid nature on its feeding strokes.
15. 7. In a turn channeling machine of the type in which the channel knife and its pressure gage are mounted on a spring-pressed slide and the edge knife and its gage are mounted on independent spring-pressed slides; the combination with said slides of means for periodically locking them against any vertical movement.
20. 8. In a channeling machine of the type in which the channel and edge knife are mounted on spring-pressed slides vertically movable in a slideway, at least one of said slides carrying a pressure gage, bearing on the sole; the combination with said slides of means operative to bind them within the slideway to, at times, change their yielding nature to a fixed or rigid nature.
25. 9. In a channeling machine of the type in which the channel and edge knife are mounted on contacting spring-pressed slides vertically movable in a single slideway, at least one of said slides carrying a pressure gage, bearing on the sole; the combination with said slides of a screw bearing on one of them, and means for rotating said screw whereby to bind said slides, at times, in said slideway and lock them against any vertical movement.
30. 10. In a turn channeling machine of the type in which the channel and edge knives are mounted on spring-pressed slides in a single slideway, and the edge knife presser gage is mounted on a third spring-pressed slide in another slideway; the combination with said slides of means operative to lock them against any vertical movement in their respective slideways.
35. 11. In a turn channeling machine of the type in which the channel and edge knives are mounted on spring-pressed slides in a single slideway, and the edge knife presser gage is mounted on a third spring-pressed slide in another slideway; the combination with said slides of a slide locking device located between said slideways constructed and arranged to exert pressure on the slides in opposite directions to bind them, at times, in their respective slideways, and means for operating said device.
40. 12. In a channeling machine of the type in which the channel and edge knife are mounted on spring-pressed slides vertically movable in a slideway, at least one of said slides carrying a pressure gage bearing on the sole; the combination with said slides of means periodically operated by the machine to bind them within the slideway and change their yielding nature to a rigid nature.
45. 13. In a turn channeling machine of the type in which the channel and edge knives are mounted on spring-pressed slides in a single slideway, and the edge knife presser gage is mounted on a third spring-pressed slide in another slideway; the combination with said slides of means periodically operated by the machine to lock them within their respective slideways against any vertical movement.
50. 14. In a channeling machine of the type in which a knife and its pressure gage are reciprocated in the line of feed, said gage being spring-pressed and acting to feed the sole on one stroke, the knife performing its function on the other stroke, and a presser foot movable to intermediately engage the sole and hold it from movement during the cutting operation; the combination with said gage of means operated periodically by the movement of said presser foot to lock said gage against any vertical movement on its feeding strokes.
55. 15. A channeling machine having, in combination, a step-by-step sole feeding member having a smooth sole engaging end held yieldingly in engagement with the sole, and means cooperating with said member to hold the sole from movement across the line of feed beneath the feeding member during the feeding steps.
60. 16. A channeling machine having, in combination, an edge gage, a sole feeding member, an expansion spring for holding said member continuously in engagement with the sole, and means to prevent compression of said spring when the sole is crowded against the edge gage in changing the direction of the feed of the sole, whereby buckling of the sole is overcome.
65. 17. A sole fitting machine having, in combination, a reciprocatory sole feeding member, a spring for holding said member continuously in engagement with the sole, and means acting automatically on each feed stroke of said member to lock it against any vertical movement.
70. 18. A channeling machine having, in com-

bination, a sole fitting knife and cooperating presser gage, a spring for holding said gage continuously in engagement with the sole, means for reciprocating said gage in the line of feed, a presser foot, means for raising said foot from the sole on the forward stroke of said gage and for lowering said foot to the sole on the backward stroke of said gage, whereby the sole is advanced 10 step-by-step, means for locking said gage against any vertical movement during its feeding stroke, and a train of mechanism connecting the presser foot and the locking means operative to actuate the locking means on each withdrawal of the foot from the sole.

19. A turn channeling machine having, in combination, a channel knife, an edge gage, means for adjusting the edge gage relatively 20 to said channel knife, a vertically movable shoulder knife, and mechanism connecting said gage adjusting means and shoulder knife constructed and arranged to insure a completion of one movement before the completion of the other.

20. A turn channeling machine having, in combination, a channel knife, an edge gage, means to move said gage toward the knife to decrease the margin on the sole, a shoulder 30 knife, means to lower said knife relatively to the sole, and a single controlling mechanism for both of said means including a locking device operating to delay the movement of the knife until the completion of the movement of the gage.

21. A channeling machine having, in combination, an edge gage, a shoulder knife, means under control of the operator for withdrawing the gage and lifting the knife, 40 means under control of the machine for advancing the gage and lowering the knife, and mechanism common to said two means for insuring a completion of one movement before the completion of the other.

22. A channeling machine having, in combination, a channel knife, an edge gage movable horizontally toward and from said channel knife, a shoulder knife movable vertically toward and from said channel knife, 50 and mechanism for moving said parts concurrently in like directions said mechanism including means for insuring that the gage movement is completed first when said parts are moved toward the channel knife and that the knife movement is completed first when said parts are moved away from the channel knife.

23. In a turn channeling machine of the type in which the edge gage is adjustable and the shoulder knife is removable from cutting position, the combination with the means for actuating said knife of a mechanism for locking it in raised position, and means for delaying the release of the lock for a time

after the release of the actuating means to 65 return the knife.

24. In a turn channeling machine of the type in which the edge gage is adjustable and the shoulder knife is removable from cutting position and both of said parts are 70 under the control of a single actuating mechanism, the combination with said mechanism of a locking device, for holding the knife in its raised position, operated by the withdrawing movement of the gage. 75

25. In a turn channeling machine of the type in which the edge gage is adjustable and the shoulder knife is removable from cutting position, said adjustment of the edge gage including a movement both toward and from the channel knife and both of said parts being under control of a single actuating mechanism, the combination with said mechanism of a locking device for holding the shoulder knife in its raised position, said device being actuated into its locking position by the movement of said gage from the channel knife and released by the movement of said gage toward the channel knife. 80

26. A channeling machine having, in combination, a channel knife, an edge gage adjustable to different distances toward and from the channel knife, and a separate actuator under control of the operator for each degree of adjustment. 90

27. A channeling machine having, in combination, a channel knife, an edge gage adjustable to different distances toward and from the channel knife, and a plurality of operating means under control of the operator for effecting such adjustments. 100

28. A channeling machine having, in combination, a channel knife, an edge gage adjustable to different distances toward and from the channel knife, and edge knife movable toward and from operating position, a single means for concurrently adjusting the edge gage and moving the edge knife, and means for adjusting the edge gage independently of said edge knife. 105

29. A channeling machine having, in combination, a channel knife, an edge gage adjustable to different distances toward and from the channel knife, an actuator under control of the operator for effecting an adjustment to one degree, a second actuator normally disengaged but engageable at the will of the operator for effecting an adjustment to a different degree. 115

30. In a channeling machine of the type in which the edge gage is adjustable toward and from the channel knife to vary the margin on the sole and mechanism under control of the operator is provided for effecting such adjustment, the combination with 120 said mechanism of two actuating devices each operable at the will of the operator independently of the other. 125

31. In a channeling machine, a channel knife reciprocable in the line of feed, an edge knife, and an edge gage located beneath the edge knife and centrally opposite the channel knife in all positions assumed by that knife. 70
32. In a channeling machine, a work support, an edge knife, means to adjust the support relatively to the knife, an edge gage beneath said knife mounted on the work support, and means for maintaining contact between the top of the gage and the under side of the knife in all positions of the work support. 75
33. In a channeling machine, an edge knife and an edge gage beneath said knife both of which are reciprocable in the line of feed, and means for continually urging said gage yieldingly upward toward said knife. 80
34. In a channeling machine, an edge gage block having a vertical slideway, an edge gage in said slideway, a spring connected to said block and gage to continuously urge said gage upward, and an edge knife above the gage. 85
35. In a channeling machine of the type in which the edge and channel knives and edge gage reciprocate in the line of feed, an edge gage holder beneath the edge knife, and means for yieldingly holding the gage in contact with the under side of the edge knife. 90
36. In a channeling machine of the type in which the edge and channel knives are blades with straight cutting edges on substantially the same line, transversely of the sole, an edge gage so located that its center is also on said line. 95
37. In a channeling machine of the type in which the channel knife is mounted on a slide in a reciprocating carrier, an edge gage connected to be reciprocated also by said carrier and located centrally opposite said channel knife. 100
38. A channel knife for sole channeling machines having a cutting blade with a longitudinal cutting edge, and a shank extending in the general direction of said cutting edge having a crook therein bowed toward the side of said cutting edge. 105
39. A channel knife for sole channeling machines having a recess in the back of its shank adjacent the heel of the cutting blade. 110
40. A presser foot for sole channeling machines having a foot to engage the sole transversely and a foot to engage the sole longitudinally, said last named foot being beveled on the upper side of its inner surface. 115
41. A presser foot for sole channeling machines having a right angular sole engaging surface one of the ends of which is beveled on its under side to avoid injuring the previously-cut channel flap in rounding a pointed toe. 120
42. In a channeling machine of the type in which the channel knife extends at an acute angle to the sole, a presser foot having a main bearing portion in advance of the knife and a supplemental portion extending beneath said knife. 125
43. In a channeling machine of the type in which the knives and pressure gages are mounted in a reciprocating carrier and a presser foot intermittently engages the sole to hold it from movement while the knives perform their function, such a presser foot having an extension which reaches forwardly in the line of feed to a position beyond said knives. 130
44. In a channeling machine of the type in which the sole is fed by pressure gages mounted in a reciprocating carrier and knives also in said carrier cut the sole on one stroke thereof, and a vertically movable presser foot intermittently engages the sole in timed relation to the reciprocations of said carrier to hold the sole from movement while being cut, such a presser foot having a main sole engaging surface extending across the line of feed and a supplemental leg projected in the line of feed of such proportions as to provide a firm bearing upon the sole when the sole is swung from beneath the main foot in channeling at the toe end. 135
45. In a channeling machine of the type in which the channel and edge knife are mounted on spring-pressed slides vertically movable in a slideway, at least one of said slides carrying a pressure gage, bearing on the sole; the combination with said slides of a slide locking device operable intermittently to lock them from movement within the slideway, mechanism under control of the operator for raising said slides from the sole and means connected with said mechanism for releasing the locking device if necessary. 140
46. In a channeling machine of the type in which a knife and its pressure gage are reciprocated in the line of feed, said gage being spring-pressed and acting to feed the sole on one stroke, the knife performing its function on the other stroke, and a presser foot movable to intermittently engage the sole and hold it from movement during the cutting operation; the combination with said gage of means operated periodically by the movement of said presser foot to lock said gage against any vertical movement on its feeding strokes, and mechanism to lift the knife from the sole, said mechanism including lock releasing means. 145
47. A channeling machine having, in combination, a sole fitting knife and cooperating presser gage, a spring for holding said gage continuously in engagement with the sole, means for reciprocating said gage in the line of feed, a presser foot, means for rais- 150

ing said foot from the sole on the forward stroke of said gage and for lowering said foot to the sole on the backward stroke of said gage, whereby the sole is advanced 5 step-by-step, means for locking said gage against any vertical movement during its feeding stroke, a train of mechanism connecting the presser foot and the locking means operative to actuate the locking 10 means on each withdrawal of the foot from the sole, and mechanism for lifting said knife and gage from the sole including means for releasing said locking means should the lifting mechanism be operated 15 while the presser foot is withdrawn from the sole.

48. A channeling machine having, in combination, a sole fitting knife and pressure gage therefor, both movable toward and 20 from the sole, means to periodically lock said knife and gage against such movement, and mechanism operable at will to lift the knife from the sole including means to release said locking means if necessary.

49. A turn channeling machine having, in combination, a channeling knife, a shoulder knife, both movable toward and from the sole, means to periodically lock said knives against such movement, and mechanism operable at will to lift the shoulder knife 30 while leaving the channel knife in operating position including means to release said locking means should said mechanism be operated while the locking means is effective.

50. In a channeling machine, an edge knife reciprocable in the line of feed, an edge gage mounted below the edge knife, and means for causing the edge gage to 40 travel with the edge knife.

51. In a channeling machine, a channel knife and an edge knife, each of the drag knife type, arranged opposite each other, and an edge gage mounted in alinement with 45 said knives.

52. A sole fitting machine having, in combination, channel and edge knives supported on vertically movable slides, means

for locking said slides against such movement, mechanism for lifting the edge knife 50 independently of the channel knife, means for locking it in raised position, an edge gage beneath said edge knife, means controlled by said mechanism for withdrawing the edge gage, supplemental means for 55 withdrawing the edge gage, and means for maintaining said edge gage in contact with the under side of said edge knife.

53. A machine of the class described, comprising, in combination, a work-guiding 60 gage, a tool progressively to operate on work guided thereby, manually-controlled means to adjust said gage, and mechanism sequentially to adjust said gage and tool and including safety locking means preventing 65 one adjustment until the other has been substantially completed.

54. A machine of the class described comprising, in combination, a work-guiding 70 gage, a tool progressively operating on work guided thereby, means for shifting the tool between operative and inoperative positions, means to vary the position of the gage with respect to the tool, an operator-controlled mechanism for actuating said means, 75 and a connection between the tool-shifting means and said mechanism constructed and arranged so that said mechanism is operative when the tool is in one only of said positions.

55. A machine of the class described comprising, in combination, a progressively-operating tool, feeding and supporting means to present work thereto and including a member which is moved to and fro in engagement with the work, a spring yieldingly to press said member against the work when it is moved in one direction, and a clamp rigidly to hold said member against the work when it is moved in the opposite direction.

56. A machine as defined by claim 58, in combination with manually-controlled means to release the work from the feeding and supporting means and to render the clamp inoperative.

FREDERIC E. BERTRAND.
